HOLDER TRAY FOR HAIR SETTING ACCESSORIES

Elaine H. Gottesman, Kew Gardens, N.Y., assignor to Elstan Products, Inc., Kew Gardens, N.Y.

Filed Feb. 2, 1965, Ser. No. 83,664

Term of patent 3½ years

(Cl. D86—10)

I claim:

The ornamental design for a holder tray for hair setting accessories, substantially as shown.
